UNITED STATES PATENT OFFICE.

WILLIAM J. KEEP, OF DETROIT, MICHIGAN.

DESIGN FOR A STOVE.

SPECIFICATION forming part of Design No. 22,688, dated August 8, 1893.

Application filed May 15, 1893. Serial No. 474,354. Term of patent 14 years.

To all whom it may concern:

Be it known that I, WILLIAM J. KEEP, a citizen of the United States, residing at Detroit, county of Wayne, State of Michigan, have in-

5 vanted a certain new and useful Design for a Stove; and I declare the following to be a full, clear, and exact description of the invention, such as will enable others skilled in the art to which it pertains to make and use the same, 10 reference being had to the accompanying drawings, which form a part of the specification.

This invention relates to stoves and has for its object, a design produced by ornamenting 15 in a peculiar way the several parts which unite to form the side of a stove.

The drawing shows in perspective a stove in which is embodied the complete design.

A, indicates the base; B, the oven door; C, 20 the door of the fire box.

E, indicates the hearth, and F, indicates the top of the stove.

G, indicates a panel of shield shape which is upon the face of the main or oven door, B.

25 The oven door B, is heavily ornamented across its lower half with scroll work and has a small ornamented scroll at its upper rear corner.

The water tank at the rear of the stove, and 30 the warming oven under it, which apparently form a single piece, are ornamented at the bottom with heavy scroll work, the scrolls extending about half way from the bottom to

the top, and the upper rear corner is ornamented with scroll work arranged in a triangular form leaving the upper part in front of the corner scroll plain. 35

The door of the fire box is ornamented with scroll work, similar to the scroll work at the bottom of the oven door. 40

The scrolls employed at the parts ornamented by them present large, smooth projecting surfaces resembling a hemispherical boss or large snail shell, making what may be called the cameo part of each scroll broad and 45 rounded, and the intaglio or sunken part narrow and deep.

A prominent feature of each of the main parts of the stove is the heavy ornamentation on the bottom, and the small corner ornament 50 at the upper rear corner, and the large intermediate portion plain, and devoid of scroll work.

What I claim is—

1. In the design for a stove, the base as 55 shown and described.

2. In the design for a stove an oven door as shown and described.

3. In the design for a stove, the water tank and warming oven as shown and described. 60

In testimony whereof I sign this specification in the presence of two witnesses.

WILLIAM J. KEEP.
